US0D1010078S

(12) **United States Design Patent** (10) **Patent No.:** **US D1,010,078 S**
(45) **Date of Patent:** ** **Jan. 2, 2024**

(54) **FAN HEATER**

(71) Applicant: **Guangzhou Tianzhi Innovation Technology Co., LTD**, Guangdong (CN)

(72) Inventor: **Xin Tian**, Guangdong (CN)

(73) Assignee: **Guangzhou Tianzhi Innovation Technology Co., LTD**, Guangdong (CN)

(**) Term: **15 Years**

(21) Appl. No.: **29/893,944**

(22) Filed: **Jun. 5, 2023**

(51) LOC (14) Cl. **23-03**

(52) U.S. Cl.

USPC **D23/332**

(58) **Field of Classification Search**

USPC D23/332, 342, 355, 364
CPC F24D 2200/08; F24D 15/02

CLAIM

The ornamental design for a fan heater, as shown and described.

DESCRIPTION

FIG. 1 is a front, right and top perspective view of a fan heater, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the fan heater that form no part of the claimed design.

1 Claim, 8 Drawing Sheets
